Crilly(57) **CLAIM**

The ornamental design for a streetlight-mountable wireless networking device, as shown and described.

DESCRIPTION

FIG. 1 is a perspective view of a streetlight-mountable wireless networking device showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof; and, FIG. 7 is a right side elevational view thereof.

The broken lines in FIGS. 1-7 form no part of the claimed design. Shading lines shown in the drawings are intended to represent approximate three-dimensional contours of the design and are not intended to indicate surface decoration.
